WHEEL COVER OR SIMILAR ARTICLE

George Albert Lyon, Detroit, Mich.

Application April 26, 1954, Serial No. 30,183

Term of patent 14 years

(Cl. D14—30)

To all whom it may concern:

Be it known that I, George Albert Lyon, a citizen of the United States and a resident of the city of Detroit, in the county of Wayne and State of Michigan, have invented a new, original, and ornamental Design for a Wheel Cover or Similar Article, of which the following is a specification, reference being had to the accompanying drawing, forming a part thereof.

In the drawing:

Figure 1 is a side elevational view of a wheel cover or similar article, showing my new design;

Figure 2 is a profile view showing the cross sectional contour of the cover member of Figure 1; and

Figure 3 is a fragmentary side perspective view of the cover member.

The dotted lines in Figures 1 and 2 showing the conventional tire and wheel assembly are for illustrative purposes only.

The dominant feature of my design resides in the full line disclosure of the drawing.

I claim:

The ornamental design for a wheel cover or similar article, substantially as shown and described.
